UNITED STATES PATENT OFFICE.

SAMUEL HODGSON, OF MEREDITH VILLAGE, NEW HAMPSHIRE.

DESIGN FOR A STOCKING.

Specification forming part of Design No. **11,262**, dated June 24, 1879; application filed April 8, 1879.
[Term of patent 3½ years.]

To all whom it may concern:

Be it known that I, SAMUEL HODGSON, of Meredith Village, Belknap county, and State of New Hampshire, have originated and designed a Pattern for Stockings, of which the following is a full, clear, and exact description, reference being had to the accompanying drawing, making part of this specification.

A represents a portion of the body and foot of a stocking, and B the band around the leg. The parts A may be made plain or ornamented with any figure that may be selected. The band B consists of alternate lines of loops of different-colored yarn around the stocking-leg, as shown on the drawing by horizontal lines at *a*. Next below these lines are short alternate vertical bars of different-colored yarn reaching around the stocking-leg, as shown at *b*. Below these bars I again insert alternate horizontal lines of loops of different-colored yarn around the leg. The latter lines are shown at *d*. Below the last-named lines I arrange long vertical bars *e* of different-col-

ored yarn followed by narrow horizontal bars *f*, of different color. This, in turn, is followed by vertical narrow bars *g*, of same color as the broad bars, or of any other color, and this is followed by narrow horizontal bars *h*, of the same color as the first narrow horizontal bars, this arrangement being the same around the entire stocking-leg.

Suitable colors should be employed and arranged to produce harmonious effect.

What I claim as my invention is—

The design for a stocking, consisting of the band around the calf of the leg, composed of the horizontal lines of loops *a*, below which are the vertical bars *b*, horizontal lines *d*, vertical bars *e*, the lines *f*, vertical bars *g*, and the horizontal lines *h*, substantially as described, and shown in the accompanying illustration.

SAML. HODGSON.
